(Cl. D1—12)

FIG. 1

FIG. 2

FIG. 3

FIG. 5

FIG. 6

FIG. 1 is a front perspective view taken from one end of a rotatable sign showing my design, the opposite end being a mirror image of the end shown;

FIG. 2, a rear elevational view thereof;

FIG. 3, a top plan view;

FIG. 4, a front perspective view taken from one end of a modified form of the rotatable signal shown in FIGS. 1 through 3, the opposite end being a mirror image of the end shown;

FIG. 5, a rear elevational view of FIG. 4; and

FIG. 6, a top plan view of FIG. 4.

This is a continuation of applications Serial Numbers D76,455 and D76,458, both filed September 3, 1963, both now abandoned.

I claim:

The ornamental design for a rotatable sign, as shown and described.
